US0D1114314S

(12) **United States Design Patent** (10) Patent No.: **US D1,114,314 S**
(45) Date of Patent: ** Feb. 17, 2026

(54) **HEAD LAMP FOR AUTOMOBILE**

(71) Applicants: **HYUNDAI MOTOR COMPANY**, Seoul (KR); **Kia Corporation**, Seoul (KR)

(72) Inventor: **Byung Kyu Park**, Hwaseong-si (KR)

(**) Term: **15 Years**

(21) Appl. No.: **35/520,599**

(22) Filed: **Mar. 4, 2024**

(80) **Hague Agreement Data**

Int. Filing Date: **Mar. 4, 2024**

Int. Reg. No.: **DM/236346**

Int. Reg. Date: **Mar. 4, 2024**

Int. Reg. Pub. Date: **Apr. 19, 2024**

(30) **Foreign Application Priority Data**

Sep. 27, 2023 (KR) 30-2023-0038489
